UNITED STATES PATENT OFFICE.

CHRISTOPHER STRACHAN, OF SOUTH ORANGE, NEW JERSEY, AND DAVID J. IRISH, OF ST. GEORGE, STATEN ISLAND, NEW YORK, ASSIGNORS TO MORSE DRY DOCK & REPAIR CO., OF NEW YORK, N. Y., A CORPORATION OF NEW YORK.

OIL PIPE AND BURNER COUPLING.

Application filed January 5, 1923. Serial No. 610,883.

To all whom it may concern:

Be it known that we, CHRISTOPHER STRACHAN and DAVID J. IRISH, citizens of the United States, residing at South Orange and St. George, Staten Island, in the counties of Essex and Richmond, and States of New Jersey and New York, respectively, have invented certain new and useful Improvements in an Oil Pipe and Burner Coupling, of which the following is a specification, reference being had therein to the accompanying drawing.

Our invention relates to improvements in couplings for connecting oil supply pipes with burners, such as those used in connection with numerous oil burning systems for boiler and other furnaces, the principal objects being to provide a simple and efficient association of parts which will prevent the burner from being withdrawn from the furnace while it is lighted, and to provide a unique construction which will permit the burner to be adjusted inwardly or outwardly as occasion may demand.

With the foregoing in view, the invention resides in the novel subject matter herein-after described and claimed, the description being supplemented by the accompanying drawings.

Figure 1 is a perspective view of our invention showing its application in connection with a burner and an air register through which said burner passes.

Figure 2 is a side elevation partly in vertical section.

Figure 3 is a plan view of the two-section bracket which rigidly carries the coupling member of the oil pipe and permits adjustment of the burner when the latter is operatively associated with said coupling member.

Figures 4 and 5 are vertical sectional views as indicated by lines 4-4 and 5-5 of Fig. 3.

In the drawings above briefly described, the numeral 1 designates an air register adapted to be secured to the front of a furnace and having a central hub 2 through which a tubular oil burner 3 passes. This burner is provided with a laterally extending neck 4 constituting a coupling member, the lower side of said neck being provided in the present disclosure, with an annular concave surface 5 to contact with an annular convex surface 6 of a stationary coupling

member 7, the latter being suitably connected with the end of a flexible oil supply pipe 8, the two coupling members 4 and 7 being clamped tightly together by means yet to be described. The common axis of the annular surfaces 5 and 6, it is to be observed, is transverse to and offset laterally from the longitudinal axis of the burner 3.

In the present showing, the coupling member 7 passes through an opening 9 in a transverse horizontal plate 10 forming an adjustable outer section of a bracket, the inner section of said bracket being preferably formed by another plate 11 which may be rigidly secured to the hub 2 or to any other suitable part by cap screws or the like 12. We prefer to provide the upper portion of the coupling member 7 with a shoulder 13 resting on the plate 10 and to thread a nut 14 on the lower end of said member 7 to contact with the lower side of said plate, thereby rigidly holding said coupling member and plate together. At opposite sides of the coupling member 7, we have shown studs 15 extending from the edges of the plate 10 to establish a pivotal connection between this plate and an arched yoke 16 which straddles the coupling member 4 and carries a set screw 17 for contact with the upper side of said coupling member. By tightening this screw, it will be seen that the two coupling members are held in operative engagement with each other, while loosening of said screw will permit the yoke 16 to be swung outwardly so that the burner 3 may be rotated and disengaged from the coupling member 7, whereupon said burner may be withdrawn. Provision is made whereby the burner cannot be withdrawn from the furnace until it is disengaged from the coupling member 7 and thus it is insured that said burner cannot be removed while the atomized fuel therefrom is ignited. Any desired adjustment of the burner inwardly or outwardly however, may be made, for which purpose the plate 10 is adjustable along the plate 11.

We prefer that the plate 10 shall rest slidably upon the upper side of the plate 11 and that it shall be provided with a rib or shoe 18 adjustably received in a longitudinal slot 19 in plate 11, said shoe being provided with a depending stud 20 upon which a nut 21 is threaded to contact with the lower side of

the plate 11 to normally hold the plate 10 against movement. By loosening this nut, the entire burner and the coupling means for the pipe 8 may be adjusted inwardly or outwardly as occasion may require. Then, by tightening the nut 21, the parts will be held rigidly in adjusted position.

Attention is directed to the fact that the bracket section or plate 11 is permanently secured to the air register 1 or to any other desired support through which the burner 3 passes and while the connection between the two bracket sections 10 and 11 permits adjustment of the former along the latter, said section 10 cannot be moved forwardly away from the section 11 and consequently, the burner 3 cannot be removed while it is in operation. In order to remove this burner, it is necessary first to release the screw 17 and swing the yoke 16 outwardly, thus permitting the coupling member 4 to be disengaged from the coupling member 7. Obviously, the oil supply through the pipe 8 should be cut off before disconnecting the coupling members 4 and 7, but if through inadvertence the supply is not shut off and thus the burner continues to operate, the passage of oil to said burner and continued operation of the latter while it is being removed, is prevented by disconnection of one of the coupling members from the other. It is thus insured that the burner cannot be removed from the furnace into the furnace room while it is blazing and thus the fire hazard is reduced to a minimum.

Attention is further directed to the fact that the connection between the coupling members 4 and 7 is broken by rotation of the burner instead of outward sliding of the latter, as in similar burner connections heretofore devised. In the connections to which we refer, an elongated male coupling member carried by the burner must be withdrawn from a stationary female coupling member, by sliding the burner outwardly, with danger of totally withdrawing the latter from the furnace while still blazing. By the construction which we employ, the burner is not moved outwardly to any extent whatever to separate the two coupling members and consequently such an occurrence cannot take place.

Further attention is directed to the relation of the contacting surfaces 5 and 6, with respect to the longitudinal axis of the burner 3. Not only does this arrangement permit separation of the two coupling members 4 and 7 by rotation of said burner, but the arrangement in question greatly facilitates re-application of the movable coupling members 4 to the stationary member 7, when the burner is reinserted into the furnace, after it has been removed for cleaning or the like. It will be observed that when re-

applying the burner, it is simply necessary to slide the latter through the hub 2 the proper extent and then rotate said burner about its longitudinal axis, so that the two coupling members may properly engage each other. During this operation, it may be necessary to effect some slight additional longitudinal sliding of the burner as the two members come together, but no lateral shifting of the burner is necessary to properly engage its coupling member with the stationary member 7.

As excellent results may be obtained from the details disclosed, they may well be followed. It is to be understood however that within the scope of the invention as claimed, numerous changes may be made.

We claim:

1. In combination, an elongated burner and means for rotatably and slidably supporting the same, said burner having a laterally extending fuel inlet neck provided with a coupling member, a stationary oil conducting coupling member normally engaged by the first named coupling member, the two coupling members having contacting co-axial annular surfaces whose common axis is transverse to and offset laterally from the longitudinal axis of the burner, and means for normally securing said coupling members together, said first named member being separable from the stationary member by merely rotating the burner about its longitudinal axis when said securing means is released.

2. In combination, a burner having a coupling member offset from the longitudinal axis of said burner, an inner bracket section adapted to be rigidly secured to a support through which the burner may be adjusted, an outer bracket section adjustable on the inner section on a line parallel with the burner axis, an oil pipe having a coupling member rigidly carried by said outer bracket section, and means for clamping the two coupling members together.

3. In combination, a burner having a coupling member offset from the longitudinal axis of said burner, an inner bracket section adapted to be rigidly secured to a support through which the burner may be adjusted, said bracket section having a slot parallel with the burner axis, an outer bracket section having a shoe and a clamping bolt passing adjustably through said slot, an oil pipe having a coupling member carried by said outer bracket section, and a clamp releasably securing the two coupling members together.

4. In combination, a bracket member adapted to be stationarily carried by a support, an oil pipe having a coupling member adjacent said bracket member, a burner adapted for slidable passage through the support, said burner having a rigid coupling

member held in detachable engagement with the first named coupling member, said coupling members being movable with respect to said bracket member when sliding said burner from one position to another, and means for holding said first named coupling member in adjusted position on the bracket

member to secure the burner in adjusted position with respect to the support.

In testimony whereof we hereunto affix 10 our signatures.

CHRISTOPHER STRACHAN.
DAVID J. IRISH.
